UNITED STATES PATENT OFFICE.

GEORGE H. TENCH, OF POTTSVILLE, PENNSYLVANIA.

CONVEYER.

SPECIFICATION forming part of Letters Patent No. 488,460, dated December 20, 1892.

Application filed July 6, 1892. Serial No. 439,142. (No model.)

To all whom it may concern:

Be it known that I, GEORGE H. TENCH, of 5
Pottsville, in the county of Schuylkill and
State of Pennsylvania, have invented a new
and Improved Conveyer or Elevator, of which
the following is a full, clear, and exact de-
scription.

The object of the invention is to provide
a new and improved conveyer or elevator,
10 which is simple and durable in construction,
very effective in operation, and provided with
buckets arranged for self-loading and self-
dumping without breaking the material, and
adapted to safely carry the material to any
15 desired distance.

The invention consists of certain parts and
details, and combinations of the same, as will
be hereinafter described and then pointed out
in the claims.

20 Reference is to be had to the accompanying
drawings forming a part of this specification,
in which similar letters of reference indicate
corresponding parts in all the figures.

Figure 1 is a side elevation of the improve-
25 ment as arranged for an elevator, parts being
in section; Fig. 2 is a front view of one of the
buckets; Fig. 3 is a sectional side elevation of
the improvement as arranged for a conveyer;
Fig. 4 is a plan view of one of the buckets and
30 the chains; and Fig. 5 is a front and elevation
of the body of the bucket.

The improved conveyer or elevator is pro-
vided with one or more chains A, A', passing
35 over sprocket wheels B and C, of which one
is the driving wheel and receives a rotary mo-
tion from suitable machinery. The chains
A, A' carry buckets D, each made in two parts,
of which one part E forms the body of the
40 bucket while the other part F forms one end
or gate for the body. The body E and gate
F are rigidly secured at E' and F' respect-
ively, to different links of the chains so that
when the latter pass over the wheels B and
45 C the gate or end F opens or closes as the case
may be. The body E of each bucket is formed
with a bottom, top and two sides, while the
ends are open; one end however, being adapt-
ed to be closed by the other part or gate F,
50 which latter is preferably made U-shaped in
cross section, that is, having an end proper
and two side flanges adapted to pass over the

sides of the body E. As shown in Fig. 1, the
device is arranged as an elevator and for this
purpose the chains A, A' are arranged ver-
55 tically and the wheel B located directly over
the wheel C. A casing G, incloses the wheel
C and is connected at one side with a chute
H, through which the material is fed to the
casing G, the bottom of which is preferably
60 semi-circular so that the buckets E fit snugly
therein. Now, when the wheel C is rotated
so that a traveling motion is imparted to the
chains A, A', and the buckets D, in the di-
rection of the arrow a', then the open end of
65 each bucket in passing through the semi-cir-
cular bottom of the casing G, gathers the ma-
terial introduced in the casing through the
chute H, so that the bucket fills itself, the
lower end being closed by the gate F. The
70 material thus held in the buckets is carried
upward and when the chain part carrying
the body E passes onto the wheel B, then the
curvature of the latter causes the link to as-
sume an inclined position to that of the ver-
75 tical part of the chain so that the body E is
thrown outward and consequently disengaged
from the gate F, whereby the material from
the body passes out of the same over the gate
F into the delivery chute I, preferably pro-
80 vided at its receiving end with an adjustable
gate J. The body E and the gate F remain
separated during the passage of the chain
around the wheel B, as will be readily under-
stood by reference to Fig. 1, the gate F again
85 closing onto the upper end of the body as
soon as the bucket D reaches the vertical
part of the chain.

As illustrated in Fig. 3, the device is ar-
ranged as a conveyer and for this purpose,
the top for each bucket may be left off as
90 shown. The horizontally traveling chains
bring the several buckets at the receiving
end of the casing K, in contact with the ma-
terial which passes down a chute K', and
through the open end of the body E' into the
95 latter, the rear end of which is closed, as soon
as the body is filled, by the gate F' at the
time the bucket reaches its lowermost posi-
tion. The bucket is then closed and remains
so in traveling through the bottom of the
100 casing K until the bucket finally comes with
its body part E to the wheel B on which the

- body swings into an annular position away from the gate F', so that the material is dumped into the chute L, leading from the end of the casing K. The body and gate remain open or disconnected during their passage around the wheel B, the two parts again closing when reaching the horizontally extending part of the chains, the buckets however, then being in an upside down position.
- 10 When the buckets pass over the wheel C at the receiving end of the casing, they separate as before described, the body is filled through its open end and closed at the rear end by the gate F', as soon as the bucket
- 15 passes to its lowermost position at the receiving end of the casing. Thus, it will be seen that the device is readily adapted for use as a conveyer or elevator. It will further be seen that the buckets are self-loading and
- 20 self-dumping and carry the material either forward or upward, as described, without disturbing in the least the position of the material in the buckets while the latter travel, thus preventing breaking of the material. It
- 25 will further be seen that by this construction the chains may be made any desired length, so as to carry the material from one point to

another, without danger of the buckets opening and scattering the contents.

Having thus fully described my invention, 30 I claim as new and desire to secure by Letters Patent,--

1. The combination with an endless chain, of a bucket rigidly connected with the chain, and an end gate forming a closure of one end 35 of the bucket, the said gate being also rigidly secured to the chain independently of the bucket, said chain being capable of flexure between the connections of the bucket and gate, and all of said parts being adapted 40 for conjoint operation, substantially as shown and described.

2. In a device of the character described, the combination, with an endless chain, of a bucket formed of a body and a gate separate 45 and independent from each other and each rigidly secured to a different link of the chain, the body having an open top and one open end, substantially as herein shown and described.

GEORGE H. TENCH.
